UNITED STATES PATENT OFFICE

RALPH S. TWOGOOD, OF SAN FRANCISCO, CALIFORNIA

COVER FOR OIL STORAGE TANKS

Application filed April 15, 1930. Serial No. 444,426.

The hereinafter described invention relates to the storage of inflammable liquids, such as crude oil, fuel oil and the like, and the exclusion of oxygen from contact with the surface of these fluids within the container as a supporter of the combustion thereof; being particularly applicable to the storage of oil in large volume as subjected to fire hazard.

Among the objects of my invention is the provision of a flexible floating roof for an oil tank or holder of construction which will through the head of the oil maintained within the holder create a substantially continuous contact of the cover with the surface of the oil, thereby excluding the air between the cover and the oil surface.

Another object of my invention is to provide a unitary type of cover construction for oil tanks of large storage capacity, such as concrete faced earthen reservoirs, which will float on top of the oil and which through the integrity of the liquid seal formed will assure the elimination of serious conflagration by exclusion of oxygen between the oil and cover surfaces.

A further object of my invention is to provide a plurality of water holding pans as a cover for inflammable liquid within a holder which will continuously reside at the liquid level and which when filled with water will serve to reduce the temperature of the liquid content and keep down the escapement of its volatile constituents.

A further object of my invention is to provide a cover and system of handling oil within a tank or holder in which the inlet and outlet of water into the tank will determine the oil level and the water will serve as a medium to float the oil into contact with a water tight flexible jointed cover composed of units made of a relatively light steel plate and which may be inexpensively constructed, thereby making possible the wide spread use of my new and novel type of cover as an effective means of safety against fire at a nominal cost.

Another object of my invention is to provide a structure of cover which will carry water over substantially the entire exterior surface thereof in a plurality of flexibly jointed pans, in fact, a water cover for the oil

stored within the tank and to float the water containing cover on the top of the oil surface so that it will always be in contact therewith in preventing the ingress of air between the under-side of the cover and the surface of the oil, as a supporter of combustion, the blanket of water on the top of the cover also acting as an element of protection against fire hazards.

In order to fully understand my invention, reference is made to the accompanying drawings in which, Fig. 1, is a plan view of the embodiment of my invention as applied to a large oil containing earthen reservoir or holder with concrete faced interior, the flexible jointed water holding pans of my construction being shown as extending longitudinally across the width of the holder, the inlet pipes for filling and discharging the oil therefrom as well as the water inlet and outlet pipes as used for floating the oil into contact with the under-side of the cover being shown.

Fig. 2 is a sectional elevation taken on line 2-2, Fig. 1, showing the structure of wooden columns, joists, stringers and sheeting upon which the flexible pans are mounted, the wooden structure serving to sustain the cover when there is little or no oil in the holder as in initially filling it or when the liquid level has been lowered temporarily as occasion may demand for cleaning, the oil weir box for maintaining the oil level against the under-side of my new and novel cover being shown.

Fig. 3 is a broken plan view of a portion of the side of the holder showing how the ends of the pans comprising my cover reside relative to the top inside contour of the holder and the pipe outlets at the pan ends used for controlling the level of water therein being shown leading into an annular trough around the top of the holder.

Fig. 4 is a sectional end view of the flexibly jointed pans of my construction as set together being taken on line 4-4, Fig. 3.

Fig. 5 is an enlarged sectional end elevation of the flexibly jointed connection of the pans of my construction showing the water level therein up to the mouth of the pipe pan outlet and below the flexible connection; this

view also showing the liquid seal effected between the surface of the oil in its contact with the under-side of the pan units of my improved cover.

5 Fig. 6 is a sectional end view taken on line 5—5, Fig. 3, showing the pan ends as set in place and mounted on the wooden super-structure, the pipe outlets of the pan being shown therein at a predetermined height de-
10 sired to maintain the water covering.

Fig. 7 is a sectional side elevation of a portion of the holder embodying the cover of my construction being taken on line 6—6, Fig. 1, and showing the water pipe line for supply-
15 ing the holder with water as used to float the oil level up in contact with the under-side of the cover, also the water weir box.

Referring to the drawings, numeral 10 denotes my flexible jointed pan constructed
20 cover as a whole and numeral 11 indicates the earthen concrete faced holder over which it resides. Numeral 12 denotes the columns of the wooden super-structure upon which my cover 10 resides, while 13 shows the joists
25 thereof and 14 the stringers upon which the wooden sheeting 15 rests. The sheeting upon which the pans of my cover 10 reside is laid with open joints 16, as shown in Fig. 5, so that the oil will have no difficulty in passing
30 through to contact the under-side of cover 10. Cover 10 as shown is composed of a series of thin metal pans preferably of steel on account of its cheapness and same may be gal-
vanized to prevent corrosion.

35 The pans when set together provide a unitary construction, the pan units being indicated by numeral 10a as shown in Fig. 5; the pans have bent up sides and ends as denoted at 10a1 and 10a2, respectively, and their edges
40 welded or otherwise sealed to form them into water holding vessels capable of floating. The pan sides 10a1 are provided with a clearance between them, as noted at X, and are held together along their top side edges in
45 flexibly jointed engagement by the edge cover cap 10a3 by rivets 10a4. The cap 10a3 serves as a water sealing joint against the ingress of rain. The separation X provides a vent for the discharge of any gas residing at the
50 surface of the oil so that it may make its exit to waste without being held or trapped as an active inflammable agent, thereby materially reducing the fire hazard from this source. The pan ends are all provided with overflow
55 pipe connections 10a5, which serve to maintain a predetermined head of water in the pans, as shown at Y, Fig. 5, so that excessive rainfall cannot reach the water flexible joint cap 10a3 but instead will be carried off to
60 waste in the concrete drain gutter 17 encompassing the top of the holder 11, through the outer ends of the overflow connections 10a5.

In this manner the pans serve as floating elements comprising the cover 10 flexibly jointed to compensate movement between

them in accommodating their bottom faces to the surface of the oil in assuring the integrity of the liquid seal therebetween. A metal coping 18 is provided around the upper concrete rim 19, of the holder 11, so that storm water will be directed into the pans of cover 10, where it can be led to waste through pan pipes 10a5, thereby assuring that the periphery of the cover in its movable engagement with the inner surface of the concrete rim 19 of holder 11 will be water tight. In making the movable engagement of cover 10 with rim 19, I carry out the edges of the wooden sheeting 15 to fit the contour of holder 11 and cover the surface of sheeting 15 a distance back from the pan ends 10a2 with thin steel liner plate 20, which serves as a chafing plate in protecting the surface of sheeting 15 against movement of the pans of the cover 10 in compensating themselves to the surface of the oil within the holder 11 in effecting the liquid seal of my invention. Numeral 21 denotes the oil weir box of holder 11 through which the oil contained within holder 11 is discharged. The pipe line 22 carries the oil out of weir box 21 to a pump, not shown, from where it is distributed as demands require.

55 The discharge of the oil from holder 11 into the weir box 21 through pipe 22 in the present embodiment of my invention occurs by displacement occasioned by water pumped into holder 11 at the bottom thereof through the pipe line 23 raising the body of oil so that its top surface contacts the under-side of the pans of cover 10. A funnel shaped outlet pipe 24 carries the oil out of holder 11 into weir box 21 from a point closely adjacent to but immediately underneath the liquid seal as made between the surface of the oil and the under-side of cover 10 so that the seal will not be impaired at any time.

60 The handling of the water as used for governing the height of the oil lever in holder 11 is controlled through water weir 25. Weir 25 is supplied from the discharge line 26 of a pump, not shown, overflowing through the weir gate into pipe line 27 which carries to the bottom of the holder 11, preferably near the center thereof. Holder 11 is filled with oil through the main supply pipe line 28.

65 In some instances in the use of my improved holder or reservoir structure, it is desirable to use the entire holding capacity thereof for the storage of oil, in which event I would dispense with the use of water as a medium with which to bring the surface of the oil in contact with the under-side of the cover in effecting the exclusion of air therebetween employing only the oil of the holder for this purpose.

70 I contemplate grounding the pans of my cover 10, so as to give a conductor of zero potential to the entire surface of the oil which my pan structure covers. This I would

do, generally speaking, by running suitable grounding wires from the ends of the pans to ground terminals. The grounded metal cover 10 of my construction gives additional protection against dangers from direct or indirect lightning.

The reservoir of my structure offers the safest protection possible to obtain for the inflammable liquid contained therein by reason of the certain exclusion of the air against the liquid surface afforded.

I desire it to be understood that the embodiment of my invention as herewith illustrated and described is typical only of its construction and functioning and that its new and novel features and advantages are equally applicable to any holder or tank whether constructed of steel concrete or earth wherein oil is stored and as such its inflammability offers a fire hazard.

Other means of controlling the inlet and outlet of the oil within holder 11 may be resorted to by me, such means requiring, however, that the liquid seal between the surface of the oil in the holder and the bottom of its floating cover 10 will always be maintained.

Minor changes may be made in the physical embodiment of the invention within the scope of the appended claims without departing from the spirit thereof.

I claim:

1. A cover for an oil storage reservoir comprising in combination a plurality of pan units connected together to form a unitary water holding structure, means for maintaining a level of water in said units, a passage between said units for the discharge of gas, and a head of water for floating said water containing and gas discharging cover on the surface of the oil in said container.

2. A cover for an oil storage reservoir comprising in combination a plurality of water carrying units, means for joining said units together, a vent at the juncture of said units for the discharge of gas, means for carrying water under head in said units, and means for exchanging oil for water within the confines of said reservoir in the maintenance of an oil seal against the bottom of said units.

3. In a cover for an oil reservoir or the like, a plurality of sheet metal pans, connecting joints between said pans, said joints having a seal for preventing the ingress of water into said pans and a passageway therebetween for the discharge of gas, and means for maintaining water in said pans at a predetermined level, said pans forming together a unitary floatable water carrying and gas discharging cover.

In witness whereof, I have hereunto set my hand at San Francisco, California, this 5th day of April, 1930.

65 RALPH S. TWOGOOD.
